UNITED STATES PATENT OFFICE

STEPHEN SCHWARTZ, OF COLUMBUS, INDIANA, ASSIGNOR TO DOHERTY RESEARCH COMPANY, OF NEW YORK, N. Y., A CORPORATION OF DELAWARE

APPARATUS FOR DISTILLING OIL

Application filed February 18, 1922. Serial No. 537,415.

This invention relates to apparatus for distilling oil, and the illustrated apparatus is particularly designed for use as a topping plant for removing the lighter constituents, 5 amounting usually to about forty percent of the whole, from crude oil, such for example, as that known to the trade as "Kansas crude", and dividing them into a series of distillates, each distillate having a boiling 10 point range within the limits fixed by commercial requirements.

An important object of the invention is to provide an apparatus for distilling oil, whereby distillation may be carried on with 15 the greatest possible conservation of heat and without superheating or cracking the oil vapors to any substantial degree.

In accordance with an important feature 20 of the invention, the oil while confined so as to retard its vaporization is subjected to intermittent heating operations, intermediate between which it is relieved from confinement and widely distributed to permit it to be vaporized in accordance with the 25 temperatures imparted to it by the heating operations and is then distilled with steam. The invention, accordingly, possesses the advantages of alternate heating and vaporization of the oil in that superheating and 30 cracking of the oil is avoided and also the advantages incident to the use of steam in distillation.

The invention further contemplates, in connection with alternately heating oil and 35 withdrawing vapors from it, condensing a portion of the vapors given off after each successive heating operation separately from the vapors given off after the preceding heating operation and then combining the 40 uncondensed portion of the vapors with the vapors given off after the preceding heating operation. In this way the constituents of the oil of like character are quite closely grouped after a single distillation.

45 A still further feature of the invention relates to the manner of re-distilling or re-running the separately condensed primary distillates, which is characterized by the re-running of the distillates in separate bodies, the residue from the bodies of lighter dis-

tillates being advanced in series to the bodies of heavier distillates. Preferably, also, the vapors leaving the bodies of distillate are scrubbed by a regulable quantity of fresh primary distillate so that only vapors of 55 definite gravity pass from the bodies. The character of the steps by which the oil is vaporized, fractionally condensed, and re-run enables it to be classified so precisely as to boiling points as not to require further 60 distillation.

In another aspect pertaining especially to the conservation of heat so as to minimize the consumption of fuel, the method of this invention possesses various features of novelty and importance. In accordance with one of such features, the vapors resulting from the primary distillation are condensed by exchange of heat between them and the incoming crude oil, and the heat in the 70 residuum from the primary distillation is utilized to re-distil the condensed distillates.

Still other important features of the invention relate to novel and improved means for heating and vaporizing the oil, condensing the oil vapors, and re-running the primary distillates. In the illustrated construction, the oil, the initial heating of which is effected in pipe coils, is charged between the successive heating operations into vapor separators equipped with baffles to facilitate the separation of vapors from the liquid oil, and the vapors are fractionally condensed in vapor heat exchangers by interchange of heat between them and the incoming crude 85 oil, the arrangement being such that the vapors given off after each heating operation pass through heat exchangers separate from those through which vapors pass from the preceding heating operation and then through the last-mentioned exchangers. The condensed distillates are supplied continuously to re-run stills constructed to enable the distillates to be heated in the presence of steam by the residuum from the primary 90 distillation. The re-run stills are connected in series so that the residue from the stills containing the lighter distillates is conducted to the stills containing the heavier distillates, and the residuum from the primary 95

distillation is caused to flow through the re-run stills counter-current to the direction of flow of the still residues. The gravity of the vapors which pass from the re-run stills is controlled by crock towers into which distillate may be directly discharged from the vapor heat exchangers.

The invention further aims to provide a final vapor separator in which the oil that passes through the pipe coils and vapor separators has evaporation completed by the heat of the flue gases leaving the pipe stills.

Although the invention is herein described as embodied in a topping plant for crude oil, it is recognized that the principles of the invention are not restricted in their application to the distillation of oil in its crude form or to the removal of the lighter constituents of the oil only. It is, therefore, intended that the scope of the invention shall not be limited except as required by the claims.

Other objects and features of the invention will be apparent as the description proceeds and will be pointed out in the claims.

The invention will be described by reference to the accompanying drawings, in which:

Fig. 1 is a diagrammatical plan view of the topping plant;

Fig. 2 is a view in elevation with parts shown in section of the plant looking from the bottom of Fig. 1;

Fig. 3 is an elevation of one of the fractional oil condensers, partly in section taken on the line 3—3 of Fig. 2;

Fig. 4 is a plan view showing the central portion of the plant including the vapor separators, fractional oil condensers, crock towers, and re-run stills and their pipe connections;

Fig. 5 is a view in elevation of the crock towers and re-run stills looking from the right in Fig. 4;

Fig. 6 is a perspective view of one of the crock tower and re-run still units;

Fig. 7 is a vertical sectional view of the final vaporizing tower;

Fig. 8 is a vertical sectional view of the initial vaporizing tower;

Fig. 9 is an end elevation of the residuum heat exchanger;

Fig. 10 is a side elevation of the heat exchanger looking from the right in Fig. 12;

Fig. 11 is a plan view of the heat exchanger;

Fig. 12 is a view in section showing the manner in which the ends of the inner tubes of the heat exchanger are mounted in the outer tubes;

Fig. 13 is a sectional elevation taken on the line 13—13 of Fig. 12;

Fig. 14 is a section taken on the line 14—14 of Fig. 10, showing the devices for supporting the inner tubes of the heat ex-

changer in properly spaced relation in the outer tubes; and

Fig. 15 is a section taken on the line 15—15 of Fig. 14.

In the present exemplification of the invention, the topping plant comprises in general, two furnace heated pipe coils, three vapor separating towers, eight vapor heat exchangers, five re-run still and crock tower units for re-distilling the primary distillates, a residuum heat exchanger, a number of box condensers of the conventional type for condensing the distillates, and coolers for such products of the operation of the plant as require cooling. For the sake of convenience of description, the vapor separating towers will generally be referred to in the ensuing specification and claims as "vapor separators", and the vapor heat exchangers which serve fractionally to condense the vapors from the vapor separators by exchange of heat between the vapors and the incoming crude oil, will generally be denoted "fractional oil condensers".

Referring to Figs. 1 and 4 of the drawings, the fractional oil condensers are designated by the numerals 2, 4, 6, 8, 10, 12, 14 and 16, and the vapor separators by the numerals 20, 22 and 24.

When the plant is in use, crude oil is forced into the fractional oil condenser 2 (Fig. 1) by a pump 26 along a pipe 28. Each of the fractional oil condensers is connected with the pipe 28 by inlet and outlet pipes 30 and 32 respectively, and between each pair of pipes 30 and 32, the pipe 28 is provided with a valve 34, which is normally closed but may be opened either partially or wholly whenever it is desired to reduce or suspend the flow of crude oil through the corresponding condenser. The pipes 30 and 32 are controlled by valves 33 (Fig. 2) which are normally open but may be closed to by-pass the flow of crude oil entirely around any of the condensers.

During the passage of the crude oil through the fractional oil condensers, an exchange of heat takes place between it and the vapors from the vapor separators, as the result of which a portion of the vapors is condensed and the temperature of the crude oil is raised. After the crude oil returns to the pipe 28 from the final condenser 16 of the series, it flows along the pipe 28 to a pipe 36 (Fig. 1), which connects with branch pipes 38 and 40 leading to the sections 42 and 44 respectively of the residuum heat exchanger 43. The residuum heat exchanger 43 is built in two sections so that half of it may be by-passed, when necessary, for repairs and during cold weather. The temperature of the crude oil is further raised in the heat exchanger 43, from which the oil issues along branch pipes 46 and 48 connected to a pipe 50. The pipe 50 then

conducts the oil to the vapor separator 20, which will be referred to hereinafter as the first vapor separator.

In the foregoing description, it has been assumed that all of the crude oil flows first through the fractional oil condensers 2, 4, 6, 8, 10, 12, 14 and 16, and then through the residuum heat exchanger 43. Under some conditions of the operation of the plant, however, it is desirable to split up the flow of the crude oil, so that half of it, for example, passes through the fractional oil condensers and the other half through the residuum heat exchanger, and then to combine the two streams of oil and charge them together into the vapor separator 20. To this end, the pipes 28 and 50 (Fig. 1) are joined by a pipe 52 on the outlet side of the fractional oil condensers, whereas on the inlet side of the condensers, the pipe 28 is connected to the pipe 36 by a pipe 54. Valves 56, 58 and 60 control the flow of oil through the pipes 36, 52 and 54 respectively. With this construction, if the valves 58 and 60 are closed and the valve 56 is open, the crude oil will flow in series through the fractional oil condensers and the residuum heat exchanger. If, however, the valve 56 is closed and the valves 58 and 60 are opened to the appropriate degree, half or any desired portion of the oil will flow along the pipe 28 to the fractional oil condensers and thence through the pipe 52 to the pipe 50, and the other half or portion will pass through the pipes 54 and 36 to the residuum heat exchanger 43 and thence to the pipe 50. The respective proportions of the oil which pass through the fractional oil condensers and the residuum heat exchanger may be varied as desired by operating the valves 58 and 60. In this manner, the crude oil may be caused to exert the requisite cooling effect on the vapors in the fractional oil condensers.

The vapor separators 20 and 22 are so nearly alike that the construction of each of them can be readily understood from examination of separator 20 shown in Figs. 2 and 8. This separator consists of a vapor separating chamber 61 and an oil reducing chamber 62. The oil to be vaporized is introduced through a pipe 50 to a distributor 63 and passes downwardly across a series of outwardly projecting conical distributing plates 64. The vaporizing oil passing from the distributing plates or baffles 64 falls upon inwardly projecting baffles 65, by which it is returned to baffles 64 lower in the separator. The vapors released from the oil pass out of the chamber 61 through outlets 66 which are located behind the baffle 65 and on the upper portion of the chamber. These outlets are located throughout the length of the chamber, which assists in carrying off the vapors without requiring

them to pass upwardly through the chamber to be scrubbed by the unvaporized oil passing downwardly through the chamber. The vapors passing through the outlets 66 are collected in a conduit 67 from which they pass to a fractional oil condenser. The oil passing from the vaporizing chamber 61 collects in an enlarged chamber 62 at the bottom of the separator. In this chamber is located a steam coil 68 by which free steam may be introduced into the body of the oil. The introduction of steam creates partial pressures within the separator to assist the vaporization of the oil, and to also aid in carrying the vapors out of the chamber. By means of the steam coil the gravity and character of the oil in the chamber 62 can be controlled as desired. An outlet 69 is provided in the bottom of the chamber by which the unvaporized residuum may be withdrawn from the separator.

By the time the crude oil has passed through the fractional oil condensers or through the residuum heat exchanger 43 or both, its temperature is raised above the boiling point of certain of its constituents. The vapor separators are designed to release vapors from the oil at atmospheric pressure. Consequently, when the oil is introduced into the vapor separator 20, a portion of it is vaporized. The vapors pass off at the top of the separator 20 through a pipe 70 to a liquid trap 71, from which the liquid is led back to the vapor separator 20 by a pipe 72. The pipe 72 is formed with a depressed portion 73 which maintains a level of liquid in the pipe so as to prevent the passage of vapors through it.

The vapors from the trap 71 pass by a pipe 74 to the fractional oil condenser 6. Each of the fractional oil condensers is formed with a vapor inlet 76 near its bottom (Fig. 3) and a vapor outlet 78 near its top, and located between the inlet 76 and outlet 78 are upper and lower partitions 80 and 82, in which are mounted the ends of open tubes 84. The pipes 30 which conduct the crude oil to the condensers communicate with them at points slightly below the upper partitions 80, and the outlet pipes 32 for crude oil are connected with the condensers at points slightly above the lower partitions 82. Baffles 86 extending inwardly from the walls of the condensers in opposite directions compel the crude oil to flow in a tortuous course about the tubes 84, thereby enhancing the exchange of heat between the crude oil and the vapors. Preferably, also a perforated plate 88 is located below the partition 82 and close to the inlet 76 of each of the condensers to throw down any liquid oil which may still remain in the vapors and to distribute the vapors uniformly in the tubes 84. The condensed distillate is withdrawn from the condensers through

seals 90 which maintain a constant liquid level in the condensers and prevent the escape of vapors from them.

The vapors from the vapor separator 20 which are not condensed in the fractional oil condenser 6 are conducted by a pipe 92 (Fig. 4) to the inlet 76 of the succeeding condenser 4, and the vapors which pass through the condenser 4 without condensation are led by a pipe 94 to the condenser 2. The most volatile vapors which escape condensation in all of the condensers 6, 4, and 2, flow through a pipe 96 (Fig. 1) to a condenser 98 of the conventional box type.

The oil which does not vaporize in the vapor separator 20 is withdrawn therefrom along a pipe 100 by a pump 102 (Fig. 1) which forces it through a heating coil or pipe still 104 into the second vapor separator 22. From the top of separator 22, the portion of the oil which vaporizes at the temperature to which the oil is raised in the heating coil 104 passes by a pipe 106 to a liquid trap 108 connected to the vapor separator 22 by a liquid return pipe analogous to the pipe 72 of the liquid trap 71. A pipe 110 receives the vapors from the trap 108 and delivers them to the inlet 76 of the fractional oil condenser 12. Steam may also be introduced in the separator 22 through a coil 111 (Fig. 1) similar to the coil 68 to assist the vaporization and to control the character of the oil. The vapors from the vapor separator 22 which are not condensed in the fractional oil condenser 12 are conducted by a pipe 112 (Fig. 4) to the condenser 10, and those which also fail of condensation in the condenser 10 pass by a pipe 114 to the condenser 8. The vapor outlet 78 of the condenser 8 communicates with the pipe 74, by which the vapors are discharged from the first vapor separator 20. Consequently, the vapors from the vapor separator 22 which remain uncondensed in passing through the fractional oil condensers 12, 10, and 8 are combined with the vapors from the first vapor separator 20 and pass with them into the condensers 6, 4, and 2.

Liquid oil is withdrawn from the separator 22 through a pipe 118 by a pump 120 and forced through a second heating coil or pipe still 122, and a pipe 123 into the final vapor separator 24. The temperature of the oil is further raised in passing through the heating coil 122 and additional heat is supplied by the oil passing through the vapor separator 24. By the time the oil reaches the bottom of the vapor separator 24, the greater portion of its most volatile constituents is separated from it. In as much as the temperature of the oil is raised gradually in the fractional oil condensers, heat exchanger 43, and heating coils 104 and 122, and opportunity is given in the separators 20, 22 and 24 for vapors to pass off, the

vapors, including even the most volatile, are not super-heated or cracked to any substantial degree.

In order to drive off the last of the light vapors from the oil which reaches the vapor separator 24, the separator is arranged to heat the oil by the exhaust flue gases from the pipe stills 104 and 122. The construction of the vapor separator 24 is shown more particularly in Figs. 2 and 7. This separator comprises an outer shell 124 which surrounds an inner exhaust flue 125. The shell 124 is mounted upon a chimney 126 for the exhaust flue gases from the pipe stills, and the flue 125 forms a continuation of the chimney 70 flue. A series of downwardly and outwardly projecting baffles 127 is secured to the flue 125, and a series of downwardly and inwardly projecting baffles 128 are secured to the shell so as to overlap the baffles 127. The 75 oil to be vaporized is led into the shell 124 through a pipe 123, to a distributor 129 which surrounds the flue 125. The oil is delivered from the distributor 129 directly 80 upon the uppermost baffle 127 and then follows a zigzag path in passing downwardly through the separator. The vapors which are released from the oil leave the separator 85 through outlets 130 which are arranged at opposite sides of the separator, there being an outlet for each pair of baffles. A 90 protecting shield 132 is placed over each outlet 130 to prevent oil from being drawn directly into the outlet. By having the outlets 130 arranged at different levels along 95 the separator the vapors are removed as formed so that there is no scrubbing action 100 of the vapors and the oil which tends to re-condense the vapors. The residuum oil 105 which reaches the bottom of the separator is collected in a manifold 134, from which it may be conducted to the re-run stills by a pipe 135. The vapors passing through the outlets 130 pass through risers 136 to a manifold 137, from which they may pass to 110 the fractional oil condensers.

With this construction the oil entering the vapor separator 24 may be reduced to any desired gravity. The greater portion of the oil is vaporized due to being heated in the pipe coil 122 and the residual vapors may be driven out of the oil in the separator 24 by means of the heat of the exhaust flue gases from the pipe still furnace. This heat is imparted directly to the flue 125 and thus acts upon the oil while it is spread in films upon the baffles 127 and 128. Preferably the shell 124 is insulated to effectively conserve the heat of the flue gases.

The vapor separator 24 (Fig. 2) is elevated above the heating coils 104 and 122, and vapor separators 20 and 22 so as to cause oil to flow by gravity to the re-run stills. The fractional oil condensers 2, 4, 6, 10, 12, 14 and 16 are also elevated at sub- 125 130

stantially the level of the separator 24 so that distillates may be discharged from them by gravity.

Heating coils are generally operated without steam, inasmuch as they have no vapor spaces. By means of the hereinbefore described construction, however, I am able to obtain in an apparatus comprising alternate heating coils and vapor separators the advantages incident to the use of steam in distillation, including lower distilling temperatures, purer distillates, and the lifting effect of the steam in removing the last portions of light oil from the body of oil being distilled. This feature of my invention is deemed of great value and importance.

The pumps 102 and 120 maintain a positive circulation of oil in the heating coils 104 and 122, which causes the oil in the coils to be uniformly heated. If a positive circulation were not maintained, portions of the oil might be vaporized in the coils and the vapors superheated and cracked, thus causing carbon to be deposited. The pipe coils would thus become obstructed, in consequence of which other portions of the oil would become superheated and more carbon would be deposited. In this manner, the pipe coils might soon become clogged to an extent such as to render further use of the apparatus impracticable until they had been taken apart and cleaned. The confinement of the oil in the heating coils 104 and 122 retards its vaporization, and, on account of the uniform heating of the oil in the coils which results from the positive circulation and unobstructed flow of the oil, very little, if any vaporization of the oil takes place in them. The pumps 26, 102, and 120 are preferably operated to effect a relatively rapid circulation of the oil through the heat exchanger 43, the fractional oil condensers, and the heating coils 104 and 122 so as to give the plant a high capacity for distillation.

Vapors are conducted from the top of the vapor separator 24 to a liquid trap 138 by a pipe 140. For convenience, the liquid trap 138 is mounted substantially at the level of the vapor separator 24 and the fractional oil condensers. A liquid outlet pipe 142 connects the bottom of the trap 138 with the bottom of the separator 24. From the trap 138, the vapors pass into a pipe 144 which leads them into the bottom of the fractional oil condenser 16 where the heavier vapors are liquefied. The remainder of the vapors issues from the upper portion of the condenser 16 into a pipe 146 which conducts them into the condenser 14. The vapor outlet 78 of the condenser 14 communicates with the pipe 110, so that the vapors from the separator 24 which are not condensed in either of the condensers 16 and 14 are combined with the vapors from the vapor sepa-

rator 22, and, in the event that they remain uncondensed, pass on through the condensers 12, 10, 8, 6, 4, and 2 and the pipe 96 to the box condenser 98.

As hitherto stated, the illustrated apparatus is particularly designed to remove the light constituents from crude oil. In the treatment of certain kinds of crude oil, for example, that commonly known as Kansas crude, these light constituents amount to about 40% of the whole. In the operation of a plant of the illustrated construction, in which the vapors from the first vapor separator pass through three fractional oil condensers, the vapors from the second vapor separator pass through three separate fractional oil condensers and then through the first three condensers, and the vapors from the third and last vapor separator pass through two condensers exclusive to it and then through the other six condensers, the distillate is divided roughly into 5% fractions. These fractions are grouped according to their boiling points, the distillate of the highest boiling point being collected in the condenser 16 and those of successively lower boiling points being brought together in the other condensers in order of their remoteness from the condenser 16. If any of the lighter portions of the oil fail of vaporization in the vapor separator 20, they will be vaporized either in the vapor separator 22 or 24, and in the vapor state will traverse the fractional oil condensers until they join in the condensers 6, 4 and 2 the portions of like volatility which were vaporized in the first vapor separator. Analogously, if any oil normally vaporizable at the temperature of the oil in the vapor separator 22 should not be vaporized in such separator, it will be vaporized in the vapor separator 24 and will then pass through the condensers 16 and 14 and join distillates of light volatility in the condensers 12, 10 and 8. In this manner, the distillates are classified so precisely in accordance with their boiling points that the fractions in the condensers 2, 4, 6, 8, 10, 12, 14 and 16 closely approach commercial requirements.

As the oil progresses through the vapor separators 20, 22 and 24 the temperature is gradually increased to drive off the higher boiling point vapors. Therefore the oil leaving the vapor separator 20 is heated in the pipe coil 104 to a higher temperature than it is heated in the fractional condensers. The oil leaving the vapor separator 22 is heated to a higher temperature in the coil 122 than the oil is heated in the coil 104. The pipe coils 104 and 122 are mounted in the same furnace (see Figs. 1 and 2). The coil 104 is mounted in the cooler or heating chamber, and the pipe coil 122 is mounted in the hotter or combustion chamber. The coils 104 and 122 consist of a series of inter-

connected pipes which extend transversely of the furnace, their ends projecting through walls 148 and 150 at opposite ends of the furnace. The individual pipes of the coils are connected by return bends and a protecting casing 152 is placed over the return bends. To heat the furnace a series of burners 154 are mounted in a Dutch oven 156 at the front of the furnace. The combustion gases from the Dutch oven pass inwardly to the combustion chamber of the furnace and pass around a series of baffles 158, (Fig. 2) to an exhaust flue 160 which connects with the chimney 126. In order to carry out the progressive heating of the oil, the oil from the separator 20 passes through the pipe 100 into the bottom of the coil 104 and leaves the top of the coil 104 in passing to the separator 22. Therefore, the oil leaving the coil 104 is in contact with the hottest gases, and the oil entering the coil 104 is in contact with the coolest gases. The oil from the separator 22 passes through a pipe 118 into the top or coolest portion of the coil 122 and leaves the bottom or hottest portion of the coil 122 through the pipe 123 in passing to the separator 24. The casings 152 around the return bends of the pipe coils are preferably provided with doors by which access may be obtained to the return bends without the necessity of entering the heating chambers of the furnace. Therefore, the return bends may be removed from the coils and the coils cleaned without previously cooling down the furnace.

The distillates which need to be redistilled are conducted from the fractional oil condensers to a series of re-run stills. The illustrated apparatus comprises five such stills designated on the drawings by the numerals 216, 218, 220, 222 and 224. The re-run stills are of like construction, the detail construction being illustrated in Fig. 6. Each re-run still comprises a cylindrical vessel having similarly located rectangular openings in its opposite ends. These openings are covered by open-ended chambers 225 and 226 having transverse cross-sections of substantially the shape and size of the openings. Perforated tube plates 228 are placed over the outer ends of the chambers 225 and 226, and to the outer sides of the plates 228 are secured respectively headers 230 and 232. Mounted in the perforations in the plates 228 are the ends of tubes 234 arranged to conduct a hot liquid from one of the headers to the other.

Each of the re-run stills is separated into a number of compartments by longitudinally disposed partitions 236 extending upwardly from the bottom of the still to a point above the level of the oil in the still. As shown, the partitions 236 are three in number and divide the still into four compartments. The upper edges of the par-

titions 236 are located in substantially the same horizontal plane at a considerable distance from the top of the still so as to provide a vapor space at the top of the still common to all of the compartments. The ends of the partitions 236 are reduced and fit into the chambers 225 and 226 against the perforated plates 228, and the partitions are provided at alternately opposite ends with openings 238 arranged in vertical rows. Oil is introduced into each of the re-run stills through an inlet 240 at one side of the chamber 225. Inasmuch as the openings 238 in the partition 236 adjacent to the oil inlet 240 are at the opposite end of the still from the oil inlet, the oil is caused to flow from the inlet to the other end of the still. From thence it passes through the openings 238 in the first partition into the next adjacent compartment of the still which it traverses in a direction opposite to the direction of its flow in the first compartment. The oil then passes through the openings 238 in the second partition and proceeds in this way through the several compartments of the still, traversing adjacent compartments of the still in opposite directions. The unvaporized portion of the oil issues from the still through an oil outlet 242 in the chamber 225.

In the operation of the apparatus the heat of the residuum is utilized to re-distill the distillates in the re-run stills. The header 230 of each of the re-run stills is provided with a residuum inlet 244 and a residuum outlet 246. Partitions 248 and 250 are provided in the headers 230 and 232 respectively, and are so arranged as to cause the residuum to flow in alternately opposite directions through the groups of pipes 234 located in the successive compartments of the still. The chamber 225 containing the oil inlet 240 and outlet 242 and the header 230 carrying the residuum inlet 244 and outlet 246 are positioned at the same end of the still, and the residuum inlet 244 and outlet 246 are located on the same sides of the still as the oil outlet 242 and inlet 240 respectively. With this arrangement, the residuum is caused to flow through the pipes 234 in the various compartments of the still in a direction opposite to the direction of the flow of the oil in the compartments.

Perforated steam pipes 252 are placed on the still bottom in each of the compartments of the still. The steam supplied by them agitates the distillates and tends to lift over the vapors, thereby reducing the temperature required for distillation. The pipes 252 of each still are connected with a header pipe 254 (Fig. 5) which communicates at one end with a steam supply pipe 256 and at the other end with an exhaust pipe 258.

The residuum draw-off pipe 185 (Fig. 5) communicates with a pipe 262 extending

along the line of re-run stills and connected to the residuum inlets 244 and outlets 246 of the stills by pipes 264 and 266 respectively. The pipes 264 and 266 are provided with valves 268, and valves 270 are located in the pipe 262 between the inlet pipe 264 and outlet pipe 266 of each still. The valves 270 are normally closed and the valves 268 open. If desired, however, any of the re-run stills may be cut off from the path of flow of the residuum by closing the valves 268 in its inlet and outlet pipes and opening the appropriate valve 270. The residuum from the final re-run still 224 of the series enters a pipe 271 and is conducted to the heat exchanger 43.

Each of the re-run stills 216, 218, 220, 222, and 224 is provided with a crock tower 272 through which vapors pass from the still. If desired, these towers may be provided with safety vacuum and pressure relief valves. In the illustrated construction, the crock towers (Figs. 2, 5, and 6) are mounted on the tops of the re-run stills adjacent to the ends of the stills at which the inlets and outlets for oil and residuum are located. The crock towers 272 (Fig. 6) consist of vertically disposed cylindrical chambers, at the bottoms of which are gratings comprising parallel bars 274 adapted to support crock tile 276. Manifestly, the crock tile may be of any desired character. Those illustrated in the accompanying drawings are formed with spiral passages for the oil and vapors, and are well adapted for use in the crock towers 272, since they present large contact surfaces. Disposed above the tile in the crock towers are four-armed spray pipes 278 whereby oil may be injected directly into the crock tower 272, and supported over the pipe 278 is a perforated baffle plate 280, the function of which is to prevent liquid oil from being mechanically transported from the crock towers by the vapors. Pipes 282 adjacent to the tops of the crock towers conduct the vapors from them to condensers 283 of the conventional box type.

The liquid oil which is discharged at the bottoms of the crock towers 272 is collected in funnel-shaped basins 284 having outlet tubes 285 arranged to deliver the oil into the compartments of the stills with which the oil inlets 240 communicate. By reason of this arrangement, oil which is condensed in a crock tower and is returned to the corresponding re-run still, and oil which first enters the re-run still by way of the crock tower is raised to the temperature of the rest of the oil in the still before it reaches the outlet 242.

The re-run stills and crock towers are not claimed per se in this application, since they are covered by my application, Serial

No. 537,414, filed Feb. 18, 1922, for apparatus for refining oil.

The means for conducting the distillate from the fractional oil condensers 2, 4, 6, 8, 10, 12, 14, and 16 to the crock towers 272 and the re-run stills comprises manifold piping 286 (Figs. 4 and 5) communicating with pipes 290 and 292, which supply the distillate to the spray pipes 278 in the crock towers 272 and to the oil inlets 240 of the re-run stills respectively. The flow of the distillate through the pipes 292 is controlled by valves 294 (Fig. 2) and the amount of distillate admitted into the crock towers through the pipes 290 and 278 is regulated by valves 296. By changing the amount of distillate introduced into any of the towers 272, the quality of the vapor evolved from the tower may be varied as desired.

Although the distillates from the fractional oil condensers are still warm when they enter the re-run stills and crock towers, the portion of the distillate which is discharged into the crock towers causes the upper portions of the towers to be relatively cool as compared with their bottom portions. Consequently, a portion of the vapors will be condensed as they rise in the crock towers. The condensed oil, however, as it flows downwardly in the crock towers meets the hot vapors rising from the still and may be again vaporized. In this way, the crock towers act continuously to re-boil the oil which results in effecting a maximum separation of the distillate within the required boiling point range.

The oil outlet 242 of the re-run still 224 connects with a pipe 298, by which the bottom oil from the still 224 is combined with the oil entering the re-run still 222 by the pipe 292. In a like manner, the bottom oil from each of the re-run stills is conducted to the next adjacent still of the series counting from the re-run still 224. The oil which is not vaporized in any of the series of stills is delivered from the plant by a pipe 300 and may be led to a cooler 302 as indicated in Fig. 1. It will be noted from the foregoing that the flow of bottom oil in the re-run stills is from the still 224 to the still 216, whereas the flow of residuum in the stills is from the still 216 to the still 224.

The apparatus is preferably equipped with coolers for cooling the lighter low boiling oil fractions which do not require to be re-run. Two such coolers 304 and 306 are indicated diagrammatically in Fig. 1 between the condenser 98 and the upper one of the condensers 283. The coolers 304 and 306 are connected to the manifold piping 286 by pipes 308 and 310 respectively.

The distillates from the fractional oil condensers 2, 4, 6, 8, 10, 12, 14, and 16 flow by gravity to the manifold piping 286 along pipes 312, 314, 316, 318, 320, 322, 324 and

326 respectively (Fig. 4). The streams of distillate from the fractional oil condensers may be sampled, and the manifold piping 286 is so arranged and controlled by valves 5 that the distillate from any of the condensers can be directed to the proper re-run still for re-distillation. Manifestly, the arrangement of the pipes and valves in the manifold 286 may vary widely. One arrangement which 10 will accomplish the desired result is illustrated diagrammatically in Fig. 1, wherein the pipe 326 leading from the fractional oil condenser 16 connects with a pipe 328, in which are two valves 330 and 332. The 15 valve 330 is normally closed and the valve 332 normally open so as to cause the distillate to be delivered to the re-run still 216. The pipes 324, 322 and 320 associated with the fractional oil condensers 14, 12 and 10 are connected with pipes 334, 336 and 338 20 arranged to deliver distillate to the re-run stills 218, 220, and 222 respectively. The pipe 334 is provided with a valve 339 disposed in the path of flow of distillate from the pipe 324 to the re-run still 218, and the pipes 336 and 338 are each equipped with valves on opposite sides of the point of connection of the pipes 322 and 320 with them. These valves are designated in Fig. 1 by the 25 numerals 340, 342, 344, and 346. Short pipes 348, 350, and 352 connect the pipes 328, 334, 336 and 338 intermediate between the valves 330, 340, and 342.

The pipes 318 and 316 leading from the 30 fractional oil condensers 8 and 6 are connected with pipes 354 and 356 respectively. The pipe 354 is provided with a valve 357, and a pipe 358 joins the pipes 338 and 354 intermediate between the valves 342 and 357. The pipe 356 is arranged to deliver distillate to the re-run still 224, and is provided 35 between the pipe 316 and the re-run still 224 with a valve 360. A pipe 362 joins the pipe 356 to the pipe 354, and a valve 364 is located in the pipe 356 between the pipes 316 and 354. A short pipe 366 controlled by a valve 368 connects the pipe 354 with the pipe 338 intermediate between the valve 346 and the re-run still 222. On the opposite side of the valve 346, the pipe 338 is connected to the pipe 336 by a short pipe 370 which is controlled by a valve 372. The pipe 370 joins the pipe 336 between the valve 344 and the re-run still 220. In a like manner, another pipe 374 having a valve 376 unites the pipes 336 and 334 between the valve 339 and the re-run still 218. The valves 330, 340, 342, 357, 368, 372 and 376 are normally closed, and the valves 332, 339, 344, 346, 364, and 360 are normally open.

With the arrangement of pipes and valves above described, the flow of distillate from the fractional oil condenser 16 may be diverted from the re-run still 216 to the still 218 by closing the valve 332 and opening the

valve 330; the flow of distillate from the fractional oil condenser 14 may be diverted from the re-run still 218 to the still 220 by closing the valve 339 and opening the valve 340; the flow of distillate from the fractional oil condenser 12 may be diverted from the re-run still 220 to the still 222 by closing the valve 344 and opening the valve 342; and the flow of distillate from the fractional oil condenser 10 may be diverted from the re-run still 222 to the still 224 by closing the valve 346 and opening the valve 357. The distillates from the fractional oil condensers 8 and 6 normally combine and flow into the re-run still 224. If desired, however, the distillate from the condenser 8 may be combined with that from the fractional oil condenser 10 and caused to flow into the re-run still 222 by closing the valve 364 and opening the valve 368. Moreover, assuming that the valve 364 is in its normally open position, if the valve 360 is closed and the valve 368 opened, the distillate from both of the fractional oil condensers 8 and 6 will be delivered into the re-run still 222. It may be desired under some conditions of operation of the plant to divert the distillate from the fractional oil condenser 10 into the re-run still 220 while the distillate from either or both of the fractional oil condensers 8 and 6 is being fed into the re-run still 222. This may be effected by closing the valve 346 and opening the valve 372. In a like manner, while the distillate from fractional oil condenser 10 is being directed to re-run still 220, the distillate from the fractional oil condenser 12 may be diverted from the re-run still 220 to the still 218 by closing the valve 344 and opening the valve 376. It will also be apparent that by closing the valve 339 and opening the valve 330, the distillate from the fractional oil condenser 14 may be combined with that from the fractional oil condenser 16 and caused to flow into the re-run still 216.

As previously indicated, it is believed that the distillates from the fractional oil condensers 2 and 4 will not ordinarily require to be re-run. In order that they may be re-run, if desired, however, the pipe 310 is connected to the pipe 338 by a short pipe 378 controlled by a valve 380, and the pipe 308 is joined to the pipe 356 by a pipe 382 controlled by a valve 384. The pipe 310 has a valve 386 between the pipe 378 and the cooler 306, and the pipe 308 has a similarly located valve 388 between the pipe 382 and the cooler 304. A pipe 390 controlled by a valve 392 connects the pipe 382 to the pipe 378 between the valve 380 and the pipe 310. When the valves 386 and 388 are closed and the valves 380 and 384 are open, the distillate from the condensers 4 and 2 will be delivered to the re-run stills 322 and 324 respectively. By opening the valve 392 and

closing the valves 380 and 386 the distillate from the condenser 4 may be caused to flow into the re-run still 224.

It is believed that it will be evident without further exposition that the illustrated arrangement of pipes and valves enables the distillate from any of the condensers 2, 4, 6, 8, 10, 12, 14, and 16 to be delivered either by itself or in combination with distillate from other condensers into any of the re-run stills or coolers where it may be desirable to deliver it. Inasmuch as it is believed that the distillate from the fractional oil condenser 16 contains sufficient light oil to justify re-running it, such distillate is, in the illustrated apparatus, delivered to the re-run stills. If, however, it should prove to be uneconomical to re-run the distillate from the condenser 16, it may be by-passed around the re-run stills to coolers and storage.

In the use of the apparatus, the distillation of the oil is carried on continuously, and the final distillates are substantially finished products requiring no further distillation. The crock towers 272 cause the finished products to be of definite gravities and boiling points, and the use of steam in the re-run stills supplements the action of the crock towers in causing the finished products to be of good quality and color.

The sections 42 and 44 of the residuum heat exchanger 43 comprise outer tubes 394 (Figs. 11, 12 and 13) each containing a number of smaller tubes 396. In the illustrated construction, seven tubes 396 (Fig. 13) are located in each of the tubes 394, and the tubes 394 are arranged in superimposed batteries of three disposed in substantially parallel horizontal planes. Adjacent tubes of the same and adjacent batteries are connected by T-shaped couplings 398 and elbows 400 so as to enable liquid to flow from one end of the heat exchanger to the other. The inner tubes 396 extend through the tubes 394 and couplings 398 and are mounted at their opposite ends in openings in plates 402 clamped between the couplings and rings 404 threaded on the elbows 400. The ends of the tubes 396 are reduced at 406 where they extend into the openings of the plates 402, and the openings of the plates 402 are enlarged on the outer side of the plate to receive glands 408 which are pressed against the tubes 396 by threaded ferrules 410. The inlet 412 for residuum is constituted by the laterally extended portion of the coupling 398 on one of the bottom tubes 394, and the residuum outlet 414 is constituted by a like portion of the coupling 398 on one of the upper tubes. The crude oil is introduced at 416 in the end of the coupling in which the residuum outlet 414 is provided and issues at 418 from the end of the coupling which contains the residuum inlet 412.

Residuum flows along the tubes 394 outside of the inner tubes 396 and passes from one to another of the tubes through the laterally extended portions of the couplings 398. The crude oil on the other hand flows through the smaller tubes 396 and elbows 400. In this manner, the crude oil and residuum are caused to flow counter-current to each other and in separate paths through the heat exchanger 43. The residuum after leaving the heat exchanger 43 may be conducted by pipes 419 and 420 to a cooler 422 (Fig. 1).

In order to prevent the tubes 396 from being distorted by their weight, the bodies of the tubes are supported in proper spaced relation to each other by spiders 423. The spiders 423 are formed to provide a central opening to receive the center tube 396, and are further provided with six equally spaced radial arms 424 which define cells adapted to receive the other tubes 396 which are arranged in a circle about the central tube. Preferably, and as shown, the circularly arranged tubes 396 are held in place in the spider 423 by metal straps 426 disposed one on each side of the spider 423.

The manner of operation of the illustrated apparatus may be briefly summarized as follows: The crude oil enters the apparatus along the pipe 28, and either the whole of the oil passes in series through the fractional oil condensers 2, 4, 6, 8, 10, 12, 14, and 16, and the residuum heat exchanger 43 to the pipe 50 and thence to the first vapor separator 20, or a portion of the oil passes through the fractional oil condensers and another portion through the heat exchanger, after which both portions of the oil again unite in the pipe 50 and are discharged into the vapor separator 20. The most volatile constituents of the oil vaporize in the separator 20 and pass off to be condensed. The liquid oil which collects in the separator is forced through the first heating coil 104 to the vapor separator 22. From the vapor separator 22, other vapors pass off to the condensers, while the liquid is pumped through the second heating coil 122 to the third vapor separator. The vaporization of oil in the separators 20 and 22 may be assisted and controlled by the admission of steam. The vaporization of oil in the final separator 24 is controlled by the heat of the exhaust flue products.

The vapors given off from the first vapor separator 20 are conducted by the pipe 74 to a fractional oil condenser 6, from whence the uncondensed portion of the vapors passes to condensers 4 and 2. The vapors from the second vapor separator 22 are led by the pipe 110 to fractional oil condenser 12 which communicates successively with fractional oil condensers 10, 8, 6, 4 and 2. The vapors from the third vapor sep-

arator 24 are delivered to the fractional oil condenser 16 and pass on through the series of condensers 14, 12, 10, 8, 6, 4, and 2, counter-current to the flow of the crude oil in the condensers. The pipe 96 conducts uncondensed vapors from the series of fractional oil condensers to the box condenser 98.

The distillates in the fractional oil condensers 16, 14, 12, 10, 8, 6, 4, and 2, are caused to flow through the manifold 286 to the re-run stills 216, 218, 220, 222, and 224 and the coolers 304 and 306. The vapors arising from the re-distillation of the distillates in the re-run stills are conducted by pipes 282 to box condensers 283.

The bottom oil in the re-run stills flows through them successively from the still 224 to the still 216 counter-current to flow of the residuum used for heating the stills, and leaves the still 216 through a pipe 300, which carries it to the cooler 302.

The residuum which issues from the separator 24 through the pipe 135 is conveyed to the re-run still 216. The residuum then passes successively through the re-run stills from the still 216 to the still 224, after which it flows along the pipe 271 to the residuum heat exchanger 43 and from thence into the cooler 422.

The distillates which collect in the condensers 98 and 283 and the coolers 304 and 306 are finished products except for treating other than distillation.

From the foregoing, it will be apparent that the heat evolved from the vapors in their condensation is utilized to raise the temperature of the crude oil and the primary distillates are re-run and the temperature of the crude oil further raised by heat recovered from the residuum. Consequently, very little, if any, heat which might be used to further the process of distillation is lost in the operation of the apparatus.

Having fully described my invention, what I claim as new and desire to secure by Letters Patent of the United States, is:

1. An oil distilling apparatus comprising a furnace, an oil heating coil mounted therein, an upright exhaust flue for said furnace, means forming a chamber around a portion of said flue, outwardly projecting baffles on said flue within said chamber, inwardly projecting baffles in said chamber, vapor outlets for said chamber and means for passing heated oil from said coil onto the upper baffles in said chamber.

2. The apparatus defined in claim 1 in which said inwardly and outwardly projecting baffles are vertically spaced apart and alternately overlap each other.

In testimony whereof I affix my signature.

STEPHEN SCHWARTZ.
